JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

TAKE-UP FOR CROCHET-MACHINES.

1,112,021.

Specification of Letters Patent. Patented Sept. 29, 1914.

Application filed January 9, 1913. Serial No. 741,060.

To all whom it may concern:

Be it known that I, JOSEPH M. MERROW, a citizen of the United States, residing in the city of Hartford, county of Hartford, State of Connecticut, have invented certain new and useful Improvements in Take-Ups for Crochet-Machines, of which the following is a full, clear, and exact specification, reference being had to the drawings and to the characters of reference thereon.

My invention relates to crochet machines and to devices for operating upon the thread thereof.

More particularly my invention relates to a device for pulling off and controlling the needle thread of machines such as the well known Merrow crochet-machines. An example of this type of machine is set forth and referred to in United States Patent #414,718 issued to myself and William H. Stedman, November 12, 1889.

Machines of this type usually employ a vertically reciprocating needle and a horizontally reciprocating crochet hook coöperating with the needle to draw loops of thread from a point within the cloth to the edge of the cloth, alternately, from above and below, and interloop these loops of thread at the edge of the cloth. Oftentimes an additional thread engaging implement is included in these machines with which the hook must coöperate in the formation of multiple thread stitches.

My invention meets the needs of either plain crochet machines, wherein a continuous series of complete single stitches are formed along the edge of the fabric, or of shell-stitch machines wherein the cloth or work is fed along once only for every several complete stitches, forming clusters of stitches at intervals along the edge of the fabric, the stitch clusters forming an ornamental border for the fabric, and has been found quite as desirable in the two thread machines as in the single thread machines. In two thread crochet machines of either of these types the second or supplemental thread is interlooped along the edge of the stitches formed by the needle thread, and is not passed through the fabric.

Considerable thread is required to form the stitches or shells and ordinarily the thread is drawn from the tensions by the stitch forming implements, and the principal object of the present device is to assist

in the drawing of the needle thread from the tension at the proper time or times and to control the slack in the thread after it is drawn from the tension, slackening the thread for the purpose of obviating undesirable strains upon the thread during portions of the cycle of stitch forming operations.

In order that the principal object of my invention may readily be understood I shall illustrate and describe an embodiment thereof.

In the drawings: Figure 1 is a front elevation of a two thread crochet or shell-stitch machine of the usual well known Merrow type, including my invention. Figs. 2, 3 and 4 show successive views of all the elements directly concerned in the operation of my device, including the device, when employed to operate upon the needle thread. The supplemental thread devices are here omitted for the sake of clearness. Fig. 5 is a plan view taken at the region of the line 5-5 of Fig. 3, showing the needle bar, the needle bar clamp and its stud, the reciprocating eye, the thread guide, the frame head, and other parts as indicated. The needle-bar and a portion of the frame head are shown in section. Fig. 1 shows the crochet hook 13 fully extended over the needle plate with the needle 12 near the top of its stroke; Fig. 2 shows the hook 13 fully retracted passing around the chaining finger and on its way down, with the needle 12 approximately in the middle position; Fig. 3 shows the hook fully extended beneath the needle plate, with the needle about at the bottom of its stroke; and Fig. 4 shows the hook again fully retracted, this time on its way up and around the edge of the chaining finger, the needle having made about half its ascending stroke and the implements returning to the positions in which they are shown in Fig. 1.

Like characters of reference throughout the drawings represent like parts.

The numeral 1 indicates the frame of the machine, 2 the hand wheel, 3 the pitman for connecting an eccentric with the needle bar lever, 4, and imparting vibrating movement thereto, 5 is the stud upon which this lever is pivoted, 6 the stud for connecting the said lever to the link, 7; 8 is the stud for connecting the link 7 with the needle bar clamp 9, and this stud is shown as a means for carry-

ing reciprocating thread engaging eye or implement 22. The needle-bar clamp 9 is clamped by means of the screw 10 to the vertically reciprocating needle-bar 11, and 12 indicates the needle. A crochet-hook 13, having a latch 13^a, coöperates with the needle to produce the stitches in the usual well known manner.

The numerals 15 and 16 indicate bosses 10 on the frame head 14, 18 indicates the needle plate, 17 the chaining finger, 19 the work plate, 20 the fabric to be finished, 21 the disks of an ordinary tension, and 22 the reciprocating thread eye having a shank 22^a and a thread passage 22^b. The stud is provided with a bore for receiving the shank 22^a of the eye 22 which is adjustably secured therein by the set screw 23. The thread guide or thread guiding arm 24 has an eye 24^a 15 and is adjustably secured to the boss 16 by the screw 25 upon which it is pivotally adjustable.

The operation of a machine such as shown and above described, provided with my invention and threaded as shown in the figures of the drawing, viz: the thread being passed from the tension to and through the eye 22 thence to and through the eye 24^a of the thread guide or arm 24 and finally to 20 and through the needle eye, and omitting reference to the supplemental thread, is substantially as follows: Beginning from the position in which the elements are shown in Fig. 2, the needle on descending passes a 25 loop of thread through the fabric in the well known manner while the hook is advancing under the chaining finger, as is shown in Figs. 2 and 3. As the needle and 30 the eye 22 ascend, the needle casts or lets off the loop passed by it through the fabric; the eye 22 begins to let out the thread passing from the tension through the thread 35 passage 22^b of the eye 22 to and through the eye 24^a, by permitting that thread to approach the straight line between the tension and the eye 24^a (from which straight line the said thread was pulled on the last descent of the eye 22); the hook in withdrawing 40 from the position shown in Fig. 3, grasps the loop passed through the fabric by the needle and pulls the same to and up around the edge of the chaining finger as 45 shown in Fig. 4. The thread guide or arm 24 with its eye 24^a is preferably so adjusted 50 that the thread forming the loop passed through the fabric by the needle and the thread let out by the eye 22, will by the time the said eye has reached the position shown in Fig. 4, be the length or quantity required 55 by the hook to form the under loop and permit the hook to rise sufficiently to clear the fabric on the succeeding advancing stroke over the fabric without the said loop unduly binding on the latch or the shank of 60 the hook when the said latch and shank are

passed therethrough. The needle and the eye 22 continue their ascent, passing through the positions shown in Fig. 4 to those shown in Fig. 1. As the eye of the ascending needle emerges from the fabric and the hook passes from the position shown in Fig. 4 to that shown in Fig. 1, (during which time the hook rises to clear the fabric prior to advancing over the fabric as shown and slips the lower loop, just formed, over its latch) the needle eye begins to act as a take up, drawing the thread between the eye 24^a and the point where the thread penetrates the fabric, out of the straight line therebetween and thus, effecting a take up action on the thread. This action of the needle takes up the thread let out by the eye 22 from about the time the eye 22 reaches the position shown in Fig. 4, when the hook has finished drawing the under loop, until the said eye has reached the end of its ascending stroke. After having reached the position shown in Fig. 1, the needle and the eye 22 begin to descend; the descending needle eye reversing its ascending action upon the thread, i. e., lets out the thread taken up on its ascent. The withdrawing hook takes the thread between the needle and the fabric drawing the same into an upper loop as it withdraws from over the fabric and drops around the chaining finger as shown in Fig. 2. The descending eye 22, begins to pull off thread from between the tension and the eye 24^a by pulling the said thread out of the straight line therebetween which thread the eye 22 will again let out on its following ascent by permitting the said thread to approach the straight line between the tension and the eye 24^a. The needle and the eye 22 continuing their descent, pass through the positions in which they are shown in Fig. 2 to those in which they are shown in Fig. 3; and as the hook advances under the chaining finger and the needle passes a loop of thread 100 through the fabric, as before, the eye 22 will complete its pulling off of the thread which, on its next ascending stroke it will pay off to the hook and to the needle eye, all as hereinabove stated.

It will be noted that the eye 22 effects its pulling off and letting out action by operating upon the thread in a path that is inclined at an acute angle to the straight line between the tension and the thread eye 24^a and that the needle eye effects its take up action by operating upon the thread in a path inclined at an acute angle to the straight line between the eye 24^a and the point of penetration of the fabric by the needle. The reciprocating elements have, therefore, a sliding action on the thread; the drawing effect on the thread produced by each of the said elements increases as the element approaches the end of its drawing

stroke and the letting out effect diminishes as the element approaches the end of its letting out stroke; the eye 22 and the needle eye may have a coöperative take up action; 5 and, a smooth and delicate action is provided; all as hereinafter more fully explained.

On the pull off stroke the eye 22 bends or 10 pulls the thread out of the straight line between the tension and the thread guide eye 24^a. At this time the pressure of engagement between the said eye and the thread is greatest, and the eye 22 slides along the thread in the direction in which 15 the thread feeds or travels. On the letting out stroke, the reciprocating eye permits the thread to approach or return to the straight line between the tension and the eye 24^a. At this time the pressure of engagement 20 between the said eye and the thread is least and the eye slides along the thread in the direction opposite to the direction of feed of the thread. Thus on the pull off stroke, the sliding of the eye 22 tends to assist the 25 pulling off action of the thread and on the letting out stroke, the effect due to the sliding of the eye is negligible.

The take up action of the needle eye is 30 designed to coöperate with the action of the eye 22, thus, on the ascending stroke of the needle eye and when the needle eye and the eye 22 are near the upper end of their stroke or after the lower loop has passed over the latch of the hook which is advancing over 35 the fabric, the drawing action of the needle eye increases as the letting out action of the eye 22 decreases and thus a slight tension is effected on the said lower loop whereby the closing of the latch by the shedding of the 40 loop is assured. On the descending stroke of the needle eye the letting out of the thread is greatest at the early part of the stroke or when the pulling off action of the eye 22 is least, and the letting out action of 45 the needle eye decreases as the pulling off action of the eye 22 increases.

The principle of taking up the thread involved in the embodiment of my invention described is particularly advantageous in 50 connection with crochet machines in which latch hooks are employed, for, in its action upon the thread the device pulls off the thread with a gradually increasing pull off action and lets out the same with a gradually decreasing pay off action, the maximum pulling off action occurring at the latter part of the stroke of the reciprocating implement and the maximum paying off action occurring at the early part of the 55 stroke. The taking up and letting out action is the same in character, the taking up of the thread gradually increasing toward the end of the stroke and the letting out thereof gradually decreasing. The action, 60 further, is sensitive, positive and accurate,

and delicate adjustments may readily be made since the reciprocating elements draw or let out only a small amount of thread as compared with their travel.

In the embodiment of my invention 70 shown and described, the tension forms an individual point of thread constraint for the portion of the thread upon which the eye 22 operates, the point of penetration of the fabric forms an individual point 75 of thread constraint for the portion of the thread upon which the needle eye effects a take up action, and the thread eye 24^a in the free end of the adjustable guide arm 24, forms a point of thread constraint 80 common to both the portion of the thread upon which the eye 22 operates and the portion of the thread upon which the needle eye effects a take up action. Further, the eye 22 coöperates with the tension and 85 the eye 24^a, and the needle eye coöperates with the point of penetration of the fabric and the eye 24^a, and, therefore, since the action of the eye 22 and the action of the needle eye both vary with the angle of inclination 90 or obliquity of the line between the points of thread constraint and the path of the reciprocating element, and since their actions both vary also with different relative 95 positions of the constraining elements and the reciprocating elements, it is obvious that by adjusting the eye 24^a about the screw 25, the operation of the eye 22 and also the take up action of the needle eye, may be simultaneously varied.

The embodiment of my invention illustrated is a form particularly adapted to be used as an attachment to a crochet machine of the class described and more especially to a machine of the well known Merrow 105 type, *e. g.*, such as is shown in Fig. 1 of the drawings accompanying United States Patent No. 1,045,163.

The stud 8, in which the eye 22 is mounted, is made interchangeable with the 110 usual screw used to connect the link 7 with the needle bar clamp 9, but may be interchangeable with the stud 6 for connecting the lever 4 with the said link, or be made interchangeable with any screw stud on the 115 needle bar actuating mechanism desired, whereby no alteration of the parts is required for its application.

The thread guiding arm 24 may be substituted for the fixed thread guide usually 120 mounted on the lower boss 16 on the frame head. This guide consists of a stud having a cylindrical body portion through which is made a thread eye and a threaded shank which is screwed into the frame. By unscrewing the said fixed thread guide the guide 24 may be secured by means of the screw 25 made to fit the threaded hole. Thus it will be seen that the guide arm 24 and the screw 25 are interchangeable with 130

the fixed thread guide usually found in the lower boss of the frame head of these machines. The guide 24, however, and the means for securing it to the desired part of a machine may be modified in any well known manner to suit the particular needs of the case.

Having thus described my invention, what I claim, and desire to secure by Letters Patent of the United States is:—

1. In a crochet machine, the stitch forming mechanism of which includes a vibratory reciprocating crochet hook operating to form overedge stitches including an upper loop and a lower loop formed from a single thread and the two loops of which are tied by a loop of the following stitch; and in combination therewith, a pair of thread supporting elements mounted one above and to one side of the other on a stationary portion of the machine, and a vertically reciprocating thread engaging implement operating upon the thread in a path the limits of which are beneath the upper and above the lower of the thread supporting elements and within the lateral distance therebetween whereby the said thread engaging implement pulls off the thread as the crochet hook forms the upper loop and lets out the same as the said hook forms the lower loop, and means for actuating and carrying the thread engaging implement.

2. In a crochet machine, including an eye pointed needle, a needle bar and a vibratory reciprocating crochet hook and in combination, a device of the class described embodying a tension and an adjustable thread guide, both mounted on a stationary portion of the machine, the tension being mounted above the thread guide and on the side of a line parallel with the needle bar opposite to that on which the thread guide is adjustably mounted, and a thread engaging implement carried by the needle bar and operating upon the thread immediately between the tension and the thread guide in a path parallel with the needle bar and between the tension and the said thread guide; whereby the thread is pulled off and let out once for each two reciprocations of the crochet hook.

3. In combination in a crochet machine including a reciprocating eye pointed needle, a device of the class described embodying a thread engaging implement reciprocating in a vertical rectilinear path, a tension mounted on one side of and above the upper end of the path of the implement and a thread guide adjustably mounted on the other side of and between the said path and the path of the needle eye, the straight line between the tension and the thread guide being inclined to the path of the implement and the straight line between the said thread guide

and the point of penetration of the needle being inclined to the path of the needle eye, 65 whereby the thread engaging implement, operating upon the needle thread held between the tension and the thread guide, may pull off thread on its descent and let out the pulled off thread on its ascent and whereby 70 the needle, operating upon the needle thread held between the said thread guide and the point of needle penetration, may take up and let out the thread; substantially as herein set forth and described.

4. In combination in a crochet machine, the stitch forming mechanism of which includes an eye pointed needle and an oscillatory crochet hook, a mechanism for operating on the thread including a tension mounted on the upper portion of the frame head of the machine, a thread guide mounted on the lower portion thereof, an eye in the said thread guide and an eye reciprocating in a path inclined to the straight line between the tension and the thread guide, the course of the thread through the elements of the device being from the tension through the reciprocating eye, through the eye of the thread guide and then through the needle eye, 90 whereby the reciprocating eye coöperating with the tension and the thread guide may operate to pull off the thread on its descent and to let out the thread to the needle and the crochet hook on its ascent substantially 95 in the manner and for the purposes herein set forth.

5. In a crochet machine including an eye pointed needle, a needle bar mounted in the frame head of the machine and mechanism for actuating the needle bar, the combination of a tension mounted on the upper portion of the frame head, an arm one end of which is adjustably secured to the lower portion of the frame head, the said arm having a thread eye through the free end thereof, situated at one side of a straight line between the point of penetration of the needle and the tension, a reciprocating eye operating on the thread between the tension and the thread eye to pull off thread on its descent and let out the same on its ascent, said needle eye operating between the thread eye and the point of penetration of the needle to take up thread on its ascent and let out the same on its descent; whereby adjustment of the position of the thread eye with respect to the tension and the point of penetration of the needle will simultaneously vary the action of the reciprocating eye and the needle eye.

JOSEPH M. MERROW.
